CLAIM

I claim, the ornamental design for an LED luminaire, as shown and described.

DESCRIPTION

FIG. 1 is a perspective view of an LED luminaire showing our new design.

FIG. 2 is a right side view of the LED luminaire shown in FIG. 1.

FIG. 3 is a left side view of the LED luminaire shown in FIG. 1.

FIG. 4 is a front view of the LED luminaire shown in FIG. 1.

FIG. 5 is a back view of the LED luminaire shown in FIG. 1.

FIG. 6 is a top view of the LED luminaire shown in FIG. 1; and,

FIG. 7 is a bottom view of the LED luminaire shown in FIG. 1.

The elements shown in broken lines are included for the purpose of illustrating portions of the LED luminaire that form no part of the claimed design.

1 Claim, 5 Drawing Sheets
